TEMPERATURE REGULATOR

Hans Otto Roosenstein, Berlin, Germany, assignor to Telefunken Gesellschaft für Drahtlose Telegraphie m. b. H., Berlin, Germany, a corporation of Germany

Application February 5, 1934, Serial No. 709,680
In Germany January 6, 1933

2 Claims. (Cl. 200—138)

This invention relates to an improved thermostat for the stabilization of temperatures in high-frequency apparatus.

Most of the frequency-governing elements in high-frequency apparatus have the property that they are dependent upon the ambient temperature. In order that disturbances due thereto may be avoided it is customary to enclose them in thermostats which serve to stabilize the temperature to the requisite degree. In most instances simple arrangements will suffice to this end, and in these what is known as a bimetal strip is employed to act as the temperature-responsive element, the said bimetal strip by way of suitable relay means cutting the heating current of the thermostat in and out in dependence upon the temperature thereof. The danger and risk of "sticking" of the contact surfaces makes it necessary in this connection to choose the current to be broken by the bimetal strip as low as possible. To this end the said bimetal strip is inserted, for instance, in the grid circuit of a triode tube in such a way that when the contact is closed the grid is fed by way of the contact surfaces with a negative biasing voltage which causes a decrease in the plate current. Now, this change of the plate current is utilized for the purpose of disconnecting and reconnecting the heating current of the thermostat by the aid of suitable relay means.

In the practical operation of arrangements of this kind it has been discovered that in the course of time changes occur in the regulating temperature. A closer examination of this condition showed that the trouble is ascribable to feeble high-frequency currents which will occasion at the contact surfaces effects of the sort usefully employed formerly in coherers. In order to overcome this difficulty very careful "choking" of the bimetal strip is necessary, though this means an undesirable complication in the arrangement.

This invention will best be understood by referring to the accompanying drawing, in which:

Fig. 1 shows an improved thermostat of this invention and a heater circuit connected thereto;

Fig. 2 is another modification of a thermostat element of this invention; and

Fig. 3 is still another embodiment of this invention, employing an external magnet for actuating the contacts of the thermostat.

Now, according to this invention the undesirable effect of radio frequency currents as stated may be considerably diminished by an arrangement whereby the contacts interrupting the current are enclosed in a thoroughly rarefied space

or chamber. Fig. 1 shows an exemplified embodiment wherein the basic idea of the invention is realized. The negative grid voltage of the triode tube 1 is connected and disconnected by the vacuum switch 2 by the aid of an operating rod 3 drawn through an elastic glass tube actuated by the bimetal strip 4 as known in the art. Included in the plate circuit of the tube is the relay 5 which serves to connect and disconnect the heating current flowing through the heater 10 winding 6. This arrangement allows of the use of vacuum switches of extremely smaller dimensions, and in this manner an excellent temperature constancy and stability is obtained. When larger switches are employed, then simpler circuit schemes may be resorted to because of the higher current-carrying capacity, the vacuum switch being then used, for instance, to directly switch the exciting current of the main relay 5 without the intermediary of the tube 1.

A particularly simple circuit scheme is realized if in lieu of the combination comprising the bimetal strip and separate vacuum switch the bimetal strip itself is provided with contact surfaces, and by disposing the device inside a vacuous space. In order that the adjustability of the temperature and of the contact lost in this arrangement may be restored, recourse may be had, for example, to a setting lever 7 or 8 (Fig. 2) actuated in the vacuum by an elastic glass tube or the like, or else by magnetic actuation of the contact motion effected from the outside as shown in Fig. 3 by magnet Mg and iron piece Fe, which is supported above the chamber and energized by a winding W.

I claim:

1. A temperature controlled switch comprising a chamber in the form of an elastic glass tube having rarefied atmosphere, each end of said chamber having a depending portion extending within the chamber, said chamber having a bi-metallic strip located within said chamber and supported by one of said depending portions, a pair of contacts within said chamber, one of said contacts located on and actuated by said bi-metallic strip, the other contact being supported by a member passing through the other depending portion of said chamber, an iron member secured on said bi-metallic strip, a magnet having a winding located outside of said chamber and arranged to actuate said switch contacts when current is passed through said windings.

2. A temperature controlled switch comprising a chamber in the form of an elastic glass tube having rarefied atmosphere, each end of said

chamber having a depending portion extending within the chamber, said chamber having a bi-metallic strip located within said chamber and supported by one of said depending portions, a 5 pair of contacts within said chamber one of said contacts located on and actuated by said bi-metallic strip, the other contact being supported

by a member passing through the other depending portion of said chamber, an iron member secured on said bi-metallic strip, an electro-magnet centrally located outside of said chamber and arranged to pass current through the windings 5 of said electro-magnet.

HANS OTTO ROOSENSTEIN.
